DESIGN FOR AN EAR ORNAMENT OR SIMILAR ARTICLE

Lorene E. Anderson, Redfield, S. Dak.

Application January 17, 1945, Serial No. 117,476

Term of patent 7 years

(Cl. D45—9)

To all whom it may concern:

Be it known that I, Lorene E. Anderson, a citizen of the United States, residing at Redfield, in the county of Spink and State of South Dakota, have invented a new, original, and ornamental Design for an Ear Ornament or Similar Article, of which the following is a specification, reference being had to the accompanying drawing, in which—

Fig. 1 is a face elevational view of an ear ornament embodying the design.

Fig. 2 is a side elevational view of the ear ornament as shown in Fig. 1.

The ornament is comprised of feathers arranged radially with small beads projecting from the center thereof as shown.

I claim:

The ornamental design for an ear ornament or similar article, as shown and described.

LORENE E. ANDERSON.
